UNITED STATES PATENT OFFICE

147,221

DESIGN FOR A SOAP DISH

Lloyd Sahley, Cleveland, Ohio

Application November 5, 1945, Serial No. 123,478

Term of patent 3½ years

(Cl. D4—3)

To all whom it may concern:

Be it known that I, Lloyd Sahley, a citizen of the United States and resident of Cleveland, Cuyahoga County, Ohio, have invented a new, original, and ornamental Design for Soap Dish, of which the following is a specification, reference being had to the accompanying drawing, forming a part thereof.

In the drawings:

Fig. 1 is a perspective view of a soap dish, showing my new design; and

Fig. 2 is a bottom plan view of same.

I claim:

The ornamental design for a soap dish, as shown.

LLOYD SAHLEY.
